U.S. Cl. 260—239 7 Claims

ABSTRACT OF THE DISCLOSURE

The compounds are 3-lower alkyl-7,8-polymethylene-1,2,3,4,5,6,7,8-octahydro-3-benzazecines (the polymethylene having from 3 to 5 carbon atoms). The compounds and their pharmaceutically acceptable acid addition and 15 quaternary ammonium salts are useful as central nervous system stimulants. The compounds can be prepared by first treating a polyhydrocycloalkano [i] quinolizine with a lower linear alkyl halide, e.g., methyl iodide to form the 20 quaternary ammonium salt thereof and then reducing the salt with sodium in liquid ammonia to form the corresponding compound, e.g., 10,11-dimethoxy-3-methyl-7,8-trimethylene-1,2,3,4,5,6,7,8-octahydro-3-benzazecine.

This invention relates to compounds of the formula:

wherein:

n is either 0, 1 or 2;

*R*¹ is a member selected from the group consisting of a hydrogen atom, hydroxy, linear alkyl having from 1 to 4 carbon atoms, e.g. methyl, ethyl, propyl and butyl, linear alkoxy having from 1 to 4 carbon atoms, e.g. 50 methoxy, ethoxy, propoxy and butoxy and, taken together with *R*², methylenedioxy

*R*² is a member selected from the group consisting of a hydrogen atom, hydroxy, linear alkyl having from 1 to 4 carbon atoms, linear alkoxy having from 1 to 4 carbon atoms and, taken together with *R*¹, methylenedioxy;

each of *R*³ and *R*⁴ is independently selected from the group consisting of a hydrogen atom, methyl and ethyl; *R*⁵ is a linear alkyl having from one to four carbon atoms; and to pharmaceutically acceptable acid addition salts thereof and pharmaceutically acceptable quaternary ammonium salts thereof.

2

Compounds I include three classes of compounds:

25 wherein *R*¹, *R*², *R*³, *R*⁴ and *R*⁵ are as defined above.

Compounds I may be prepared according to the following reaction scheme wherein *n*, *R*¹, *R*², *R*³, *R*⁴ and *R*⁵, are as defined above, and *X* is a chloro, bromo and iodo.

According to the reaction scheme, Step (a) is effected by treatment of a polyhydrocycloalkano [i] quinolizine (Compound II) with a lower alkyl halide (*R*⁵*X*), e.g., *CH*₃*I*, preferably in a solvent, e.g., ethanol, to obtain Compound III, i.e., the quaternary ammonium salt of Compound II.

In Step (b) the Compound III is reduced by sodium in liquid ammonia to obtain the corresponding Compound I.

Compounds II, e.g., 11,12-dimethoxy-2,3,3a,4,5,6,8,9-octahydro-1H-benzo[a]cyclopenta[i]quinolizine may be obtained according to the procedures described in United States Patent 3,210,357 of William I. Taylor et al. issued 65 Oct. 5, 1965.

Compounds I and their pharmaceutically acceptable acid addition and quaternary ammonium salts are useful as central nervous system stimulants. They are administered to mammals either orally or parenterally in daily doses of from 0.5 to 5 mg./kg. of body weight, e.g. from 30 to 300 milligrams per diem, preferably administered in divided doses from 2 to 4 times a day; a single daily oral dose is also acceptable.

The acid addition and quaternary ammonium salts of Compounds I are prepared according to well-known procedures from Compounds I. They are all useful, in accord with recognized procedures, for the preparation of corresponding pharmaceutically acceptable salts.

Among the pharmaceutically acceptable acid addition salts are salts of organic acids, e.g. tartaric acid; inorganic acids, e.g. hydrochloric acid, hydrobromic acid and sulfuric acid; monobasic acids, e.g. an alkylsulfonic acid, such as methylsulfonic acid ($\text{H}_3\text{C}-\text{SO}_3\text{H}$); dibasic acids, e.g. succinic acid; tribasic acids, e.g. phosphoric acid and citric acid; saturated acids, e.g. acetic acid; ethylenically unsaturated acids, e.g. maleic acid and fumaric acid; and aromatic acids, e.g. salicylic acid and arylsulfonic acids, such as phenylsulfonic acid. The only limitation on the acid is that the resulting salt be pharmaceutically acceptable; it is preferred, however, that the acid addition salt be water-soluble.

Each of the pharmaceutically active compounds of this invention may be, e.g. incorporated, for oral administration, in a tablet as the sole active ingredient. A typical tablet is constituted by from 1 to 3 percent binder, e.g. tragacanth; from 3 to 10 percent disintegrating agent, e.g. corn starch; from 2 to 10 percent lubricant, e.g. talcum; from 0.25 to 1.0 percent lubricant, e.g. magnesium stearate; an average dosage of active ingredient; and q.s. 100 percent of filler, e.g. lactose; all percentages being by weight. Tablets are prepared according to standard tabletting techniques, which are well-known in the art, employing the necessary amounts of conventional granulating liquids, e.g. alcohol SD-30 and purified water. An exemplary tabletting formulation for the instant active compounds is:

	Parts
Title compound of Example 1	30
Tragacanth	2
Lactose	59.5
Corn starch	5
Talcum	3
Magnesium stearate	0.5
Alcohol SD-30, purified water, q.s.	

Examples illustrative of this invention follow. In the examples all temperatures are in degrees centigrade and all percents and parts are by weight, unless specified otherwise. Parts by weight are related to parts by volume as a kilogram is related to a liter.

EXAMPLE 1

10,11-dimethoxy-3-methyl-7,8-tetramethylene-1,2,3,4,5,6,7,8-octahydro-3-benzazecine

This example illustrates the preparation of a compound Ib according to the reaction scheme presented above.

(a) Preparation of 12,13-dimethoxy-1,2,3,4,4a,5,6,7,9,10-decahydro-benzo[a]cyclohexa[i]quinolizine methiodide

Dissolve 25 parts of 12,13-dimethoxy-1,2,3,4,4a,5,6,7,9,10-decahydro-1H-benzo[a]cyclohexa[i]quinolizine in 50 parts by volume of ethanol and 50 parts by volume of methyl iodide. Heat the solution under reflux for 3 days. Concentrate the reaction mixture under vacuum to obtain a residue which is then triturated with 150 parts by volume of ether and collect the resultant solid by filtration to obtain compound (a).

12,13 - dimethoxy-1,2,3,4,4a,5,6,7,9,10-decahydro-1H-benzo[a]cyclohexa[i]quinolizine is obtainable by the procedure of Example 3 of United States Patent 3,210,357 noted above.

(b) Preparation of 10,11-dimethoxy-3-methyl-7,8-tetramethylene-1,2,3,4,5,6,7,8-octahydro-3-benzazecine

Add 8 parts of sodium to a stirred suspension of 30 parts of compound (a) (12,13-dimethoxy-1,2,3,4,4a,5,6,7,9,10 - decahydro - benzo[a]cyclohexa[i]quinolizine methiodide) in 500 parts by volume liquid ammonia cooled in a Dry Ice-acetone mixture. Stir the mixture for one hour, then allow to evaporate for 16 hours. Add to the residue aqueous methanol and extract with chloroform. Dry the chloroform extract over sodium sulfate and evaporate under vacuum. Crystallize the residue twice from ethanol to obtain the title product, melting point (M.P.), 85° to 86° C.

In Step (a) replacing the methyl iodide with propyl bromide results in the preparation, in a similar manner, of the corresponding compound III and the corresponding compound I, according to Step (b).

Replacing the 12,13 - dimethoxy - 1,2,3,4,4a,5,6,7,9,10-decahydrobenzo[a]cyclohexa[i]quinolizine in Step (a) with 12,13-dipropyl- or 12,13-methylenedioxy-1,2,3,4,4a,5,6,7,9,10-decahydrobenzo[a]cyclohexa[i]quinolizine results in the preparation, in a similar manner, of the corresponding compounds III, and from which the corresponding compounds I, may be prepared according to Step (b).

EXAMPLE 2

10,11-dimethoxy-3-methyl-7,8-trimethylene-1,2,3,4,5,6,7,8-octahydro-3-benzazecine bimaleate

This example illustrates the preparation of a compound Ib by a procedure similar to the procedure described in Example 1.

5

(a) Preparation of 11,12-dimethoxy-2,3,3a,4,5,6,8,9-octahydro-1H-benzo[a]cyclopenta[i]quinolizine methiodide

5

10

Dissolve 20 parts of 11,12-dimethoxy-2,3,3a,4,5,6,8,9-octahydro-1H-benzo[a]cyclopenta[i]quinolizine in 80 parts by volume ethanol and 50 parts by volume methyl iodide. Heat solution under reflux for 3 days. Concentrate the reaction mixture and recover the solids. Triturate the solids with ethanol-ether and collect by filtration. Recrystallize from ethanol to obtain the methiodide (compound (a)), M.P. 213° to 215° C.

11,12-dimethoxy-2,3,3a,4,5,6,8,9-octahydro-1H-benzo[a]cyclopenta[i]quinolizine is obtainable by the procedure of Example 1 of United States Patent 3,210,357 noted above.

(b) Preparation of 10,11-dimethoxy-3-methyl-7,8-trimethylene-1,2,3,4,5,6,7,8-octahydro-3-benzazecine bimaleate

Following the procedure of Example 1, add 5 parts of sodium to 20 parts of compound (a), (11,12-dimethoxy-2,3,3a,4,5,6,8,9-1H-benzo[a]cyclopenta[i]quinolizine methiodide) in 400 parts by volume of liquid ammonia. Stir the mixture for one hour then allow to evaporate for 16 hours. Dissolve the residue in aqueous methanol and extract with chloroform. Dry the chloroform extract and evaporate under vacuum to obtain a residue, which then convert to the bimaleate salt by conventional procedure to obtain the title product, M.P. 170° to 172° C.

In Step (a) replacing the 11,12-dimethoxy-2,3,3a,4,5,6,8,9-octahydro-1H-benzo[a]cyclopenta[i]quinolizine with 11,12-dibutyl- or 11-hydroxy-2,3,3a,4,5,6,8,9-octahydro-1H-benzo[a]cyclopenta[i]quinolizine results in the preparation, in a similar manner, of the corresponding compound II from which the corresponding compound I may be obtained according to Step (b). In a similar manner, by selecting appropriate starting materials compounds Ic may be prepared, e.g. 10,11-dimethoxy-3-methyl-7,8-pentamethylene-1,2,3,4,5,6,7,8-octahydro-3-benzazecine.

What is claimed is:

1. A member selected from the group consisting of the free base, a pharmaceutically acceptable acid addition salt thereof and a pharmaceutically acceptable quaternary

6

ammonium salt thereof; the free base being of the formula:

wherein:

- n* is either 0, 1 or 2;
- 15 R¹ is a member selected from the group consisting of a hydrogen atom, hydroxy, linear alkyl having from 1 to 4 carbon atoms, linear alkoxy having from 1 to 4 carbon atoms and, taken together with R², methylene-dioxy;
- 20 R² is a member selected from the group consisting of a hydrogen atom, hydroxy, linear alkyl having from 1 to 4 carbon atoms, linear alkoxy having from 1 to 4 carbon atoms and, taken together with R¹, methylene-dioxy;
- 25 each of R³ and R⁴ is independently selected from the group consisting of a hydrogen atom, methyl and ethyl; and
- R⁵ is a linear alkyl having from one to four carbon atoms.
- 30 2. A compound according to claim 1 wherein *n* is 0.
3. A compound according to claim 2 which is 10,11-dimethoxy-3-methyl-7,8-trimethylene-1,2,3,4,5,6,7,8-octahydro-3-benzazecine bimaleate.
- 35 4. A compound according to claim 1 wherein *n* is 1.
5. A compound according to claim 4 which is 10,11-dimethoxy-3-methyl-7,8-tetramethylene-1,2,3,4,5,6,7,8-octahydro-3-benzazecine.
- 40 6. A compound according to claim 1 wherein *n* is 2.
7. A compound according to claim 6 which is 10,11-dimethoxy-3-methyl-7,8-pentamethylene-1,2,3,4,5,6,7,8-octahydro-3-benzazecine.
